RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed September 26, 1929. Serial No. 395,333.

My invention relates to railway traffic controlling apparatus, and particularly to the train-carried portion of continuous inductive train control systems of the code 5 type.

One feature of my invention is the provision of means for checking the operation of the acknowledging relays commonly employed in systems of this type.

10 I will describe one form of apparatus embodying my invention, and will then point out the novel features thereof in claims.

The accompanying drawing is a diagrammatic view showing one form of train-carried 15 apparatus embodying my invention.

Referring to the drawing, the apparatus comprises three relays R^3 , R^2 and R^1 , which relays are commonly known as the "authorized", "approach restricting" and "slow" relays in a coded continuous inductive train 20 control system. These relays are controlled in such manner that relays R^3 and R^1 are energized under "authorized" conditions; relay R^2 and R^1 are energized under "approach 25 restricting" conditions; relay R^1 alone is energized under "slow" conditions, and all three of the relays are de-energized under "stop" conditions. These relays may be controlled by the apparatus illustrated and described in application for Letters Patent of 30 the United States filed by Lloyd V. Lewis on August 2nd, 1927, Serial No. 210,165, for railway traffic controlling apparatus. The transformer, the filter circuits, and the rectifiers 35 which supply current to these relays are illustrated in the present drawing merely for purposes of convenience, but they are not provided with reference characters, because they form no part of my present invention.

40 Associated with the relays R are three stick relays S^3 , S^2 and S^1 , which relays are known as "acknowledging" relays. The reference character a designates a manually operable acknowledging switch having a normally open contact 71 and a normally closed contact 52. When this switch is operated, the normally open contact 71 becomes closed, and the normally closed contact 52 becomes opened.

45 The reference character 55 designates a

brake controlling magnet which is normally energized, but which when deenergized serves to cause an automatic application of the brakes. This magnet is controlled by the relays R and S in the manner which I will now 55 describe.

When the train is traveling under authorized conditions, relays R^3 and R^1 are energized, as hereinbefore stated, and relays S^1 , S^2 and S^3 are all de-energized. The brake 60 controlling magnet 55 is then energized by virtue of a circuit which passes from terminal B of a suitable source of current, through front contact 39 of relay R^3 , back contact 50 of relay S^3 , back contact 198 of relay S^2 , contact 52 of the acknowledging switch a , winding of magnet 55, back contact 182 of relay S^2 , back contact 57 of relay S^3 , and front 65 contact 46 of relay R^3 to terminal O of the same source of current. 70

Assuming now that the conditions under which the train is traveling become changed, so that relay R^3 becomes de-energized and relay R^1 becomes energized, the circuit just traced for magnet 55 will be opened at front 75 contacts 39 and 46 of relay R^3 , so that unless another circuit for magnet 55 becomes closed, an automatic application of the brakes will occur. When this change takes place, if the engineer momentarily reverses the acknowledging switch a , a pick-up circuit for relay S^1 will become closed, which circuit is from terminal B, through back contact 39 of relay R^3 , contact 71 of switch a , the winding of relay S^1 , and back contact 46 of relay R^3 to 80 terminal O. The closing of relay S^1 closes a pick-up circuit for relay S^2 , which circuit is from terminal B, through back contact 39 of relay R^3 , front contact 78 of relay S^1 , the winding of relay S^2 , and back contact 46 of relay R^3 to 85 terminal O. The closing of relay S^2 closes a pick-up circuit for relay S^3 , which circuit is from terminal B, through the back contact 39 of relay R^3 , front contact 98 of relay S^2 , the lower winding of relay S^3 , and back contact 46 to terminal O. A stick circuit for relay S^3 then becomes closed, which circuit is from terminal B, through the back contact 39 of relay R^3 , front contact 61 of relay R^2 , front contact 87 of relay S^3 , the upper 90

winding of relay S^3 , and back contact 46 of relay R^3 to terminal O. As soon as the acknowledging switch a is restored to its normal condition the pick-up circuit for relay S^1 becomes opened at contact 71, and the pick-up circuit for relay S^2 then becomes open at contact 78 of relay S^1 with the result that relay S^3 remains energized, but relays S^1 and S^2 both become de-energized. A second circuit for the brake magnet 55 is then closed, which circuit passes from terminal B, through back contact 39 of relay R^3 , front contact 61 of relay R^2 , front contact 50 of relay S^3 , back contact 198 of relay S^2 , contact 52 of the acknowledging switch a , winding of magnet 55, back contact 182 of relay S^2 , front contact 57 of relay S^3 , and back contact 46 of relay R^3 to terminal O. The train may therefore proceed without an automatic application of the brakes.

I will next assume that the conditions under which the train is traveling change to "slow", so that relay R^2 becomes de-energized, leaving relay R^1 as the only one of the R relays which is energized. The opening of relay R^2 will open the stick circuit for relay S^3 , so that the latter relay will become de-energized. If the engineer does not operate the acknowledging switch, magnet 55 will become de-energized to cause an automatic application of the brakes. If the engineer does reverse the acknowledging switch a , relays S^1 will become energized as before, and this will cause relay S^2 to become energized as before, and this will in turn cause relay S^3 to become energized as before. Relay S^2 will then remain energized by virtue of a stick circuit which passes from terminal B, through back contact 39 of relay R^3 , back contact 61 of relay R^2 , front contact 92 of relay R^1 , front contact 198, and front contact 82 of relay S^2 , winding of relay S^2 , and back contact 46 of relay R^3 to terminal O. After the acknowledging switch a is restored to its normal position, relay S^2 will remain energized due to this stick circuit, and relay S^3 will remain energized because its pick-up circuit is closed at contact 98 of relay S^2 . A third circuit for the brake magnet 55 will then be closed, which circuit passes from terminal B, through back contact 39 of relay R^3 , back contact 61 of relay R^2 , front contact 92 of relay R^1 , front contact 198 of relay S^2 , contact 52 of acknowledging switch a , winding of brake magnet 55, front contact 182 of relay S^2 , and back contact 46 of relay R^3 to terminal O. It follows that the train may then proceed without an automatic application of the brakes.

I will now assume that the train enters an occupied block or territory which is not equipped for automatic train control, so that relay R^1 becomes de-energized. The opening of this relay will open the stick circuit

for relay S^2 , so that the latter relay will then open, with the result that relay S^3 will, likewise, open. If the engineer does not operate the acknowledging switch a , magnet 55 will become de-energized and an automatic application of the brakes will occur. If the engineer does operate the acknowledging switch a , however, relay S^1 will become energized by virtue of the pick-up circuit traced hereinbefore, and a stick circuit for this relay will then become closed, which circuit passes from terminal B, through back contact 39 of relay R^3 , back contact 61 of relay R^2 , back contact 92 of relay R^1 , front contact 103 of relay S^1 , winding of relay S^1 , and back contact 46 of relay R^3 to terminal O. Relay S^2 will become energized because relay S^1 is closed, and relay S^3 will become energized because relay S^2 is closed. A fourth circuit for magnet 55 will now be closed, which circuit passes from terminal B, through back contact 39 of relay R^3 , front contact 78 of relay S^1 , front contact 82 of relay S^2 , acknowledging switch contact 52, winding of brake valve magnet 55, front contact 182 of relay S^2 , and back contact 46 of relay R^3 to terminal O. It follows that the train may then proceed without an automatic application of the brakes.

Assuming now that the traffic conditions under which the train is traveling change so that relays R^3 and R^1 become energized, the stick circuit for relay S^1 will be opened at contact 92 of relay R^1 , so that all of the relays S^1 , S^2 and S^3 should release. The same thing will be true if the conditions change so that relays R^1 and R^2 become energized. It will be noted that the first circuit for brake valve magnet 55 includes back contacts of relays R^2 and R^3 , and that the second circuit for this magnet includes a back contact of relay S^2 . It follows that when traffic conditions change from "stop" to "authorized", brake valve magnet 55 cannot become energized unless both of the relays S^2 and S^3 open their front contacts and close their back contacts. Similarly, when traffic conditions change from "stop" to "approach restricting", this magnet cannot become energized unless relay S^2 opens. Apparatus constructed in accordance with my invention serves, therefore, as a check on the correct operation of the stick relays S^2 and S^3 . That is, it serves as a check on the release of these relays when conditions change from less favorable to more favorable, because a failure of either of these relays to release will result in an automatic application of the brakes.

This check makes it possible to use small light relays of the telephone type for relays S^2 and S^3 , thereby reducing the weight and cost of the train-carried equipment, and, of course, also reducing the space occupied by this equipment.

Although I have herein shown and described only one form of apparatus embody-

ing my invention, it is understood that various changes and modifications may be made therein within the scope of the appended claims without departing from the spirit and scope of my invention.

5 Having thus described my invention, what I claim is:

1. Train carried railway traffic controlling apparatus comprising three relays R^1 , R^2 and R^3 , controlled in such manner that relays R^1 and R^3 are energized under "authorized" conditions, relays R^1 and R^2 are energized under "approach restricting" conditions, relay R^1 alone is energized under "slow" conditions, and all three relays are de-energized under "stop" conditions; three stick relays S^1 , S^2 and S^3 , a manually operable acknowledging switch a having a normally open contact 71, a pick-up circuit for relay S^1 including a back contact of relay R^3 and said contact 71, a pick-up circuit for relay S^2 including a back contact of relay R^3 and a front contact of relay S^1 , a pick-up circuit for relay S^3 including a back contact of relay R^3 and a front contact of relay S^2 , a stick circuit for relay S^3 including a back contact of relay R^3 and a front contact of relay R^2 , a stick circuit for relay S^2 including a back contact of relay R^3 and a back contact of relay R^2 as well as a front contact of relay R^1 , a stick circuit for relay S^1 including back contacts of relays R^3 , R^2 and R^1 , a brake valve magnet, a first circuit for said magnet including a front contact of relay R^3 and a back contact of each relay S^3 and S^2 , a second circuit for said magnet including a back contact of relay R^3 and a front contact of relay R^2 as well as a front contact of relay S^3 and a back contact of relay S^2 , a third circuit for said magnet including back contacts of relays R^3 and R^2 as well as a front contact of relay R^1 and a front contact of relay S^2 , and a fourth circuit for said magnet including a back contact of relay R^3 and a front contact of relay S^1 as well as a front contact of relay S^2 .
2. Train carried railway traffic controlling apparatus comprising three relays R^1 , R^2 and R^3 , controlled in such manner that relays R^1 and R^3 are energized under "authorized" conditions, relays R^1 and R^2 are energized under "approach restricting" conditions, relay R^1 alone is energized under "slow" conditions, and all three relays are de-energized under "stop" conditions; three stick relays S^1 , S^2 and S^3 , a manually operable acknowledging switch a having a normally open contact 71, a pick-up circuit for relay S^1 including a back contact of relay R^3 and said contact 71, a pick-up circuit for relay S^2 including a back contact of relay R^3 and a front contact of relay S^1 , a pick-up circuit for relay S^3 including a back contact of relay R^3 and a front contact of relay S^2 , a stick circuit for relay S^3 including a back contact of relay R^3 , a stick circuit for relay S^2 including a back contact of relay R^3 and a front contact of relay R^1 , a stick circuit for relay S^1 including back contacts of relays R^3 , R^2 and R^1 , a brake valve magnet, and a main circuit for said magnet including back contacts of said relays S^2 and S^3 and a front contact of said relay R^3 .
3. Train carried railway traffic controlling apparatus comprising three relays R^1 , R^2 and R^3 , controlled in such manner that relays R^1 and R^3 are energized under "authorized" conditions, relays R^1 and R^2 are energized under "approach restricting" conditions, relay R^1 alone is energized under "slow" conditions, and all three relays are de-energized under "stop" conditions; three stick relays S^1 , S^2 and S^3 , a manually operable acknowledging switch a having a normally open contact 71, means operating if the engineer closes contact 71 upon a change from authorized to approach restricting conditions to energize relays S^1 , S^2 and S^3 in succession and to subsequently keep relay S^3 energized, means operating if the engineer closes contact 71 upon a change from approach restricting to slow conditions to energize relays S^1 , S^2 and S^3 in succession and to subsequently keep relays S^2 and S^3 energized, means operating if the engineer closes contact 71 upon a change from slow to stop conditions to energize all of said acknowledging relays and to keep them energized, a brake valve magnet, a first circuit for said magnet including a front contact of relay R^3 and a back contact of each relay S^3 and S^2 , a second circuit for said magnet including a back contact of relay R^3 and a front contact of relay R^2 as well as a front contact of relay S^3 and a back contact of relay S^2 , a third circuit for said magnet including back contacts of relays R^3 and R^2 as well as a front contact of relay R^1 and a front contact of relay S^2 , and a fourth circuit for said magnet including a back contact of relay R^3 and a front contact of relay S^1 as well as a front contact of relay S^2 .
4. Train carried railway traffic controlling apparatus comprising three relays R^1 , R^2 and R^3 , controlled in such manner that relays R^1 and R^3 are energized under "authorized" conditions, relays R^1 and R^2 are energized under "approach restricting" conditions, relay R^1 alone is energized under "slow" conditions, and all three relays are de-energized under "stop" conditions; three stick relays S^1 , S^2 and S^3 , a manually operable acknowledging switch a having a normally open contact 71, means operating if the engineer closes contact 71 upon a change from authorized to approach restricting conditions to energize relays S^1 , S^2 and S^3 in succession and to subsequently keep relay S^3 energized, means operating if the engineer closes contact 71 upon a change from approach restricting to slow

conditions to energize relays S^1 , S^2 and S^3 in succession and to subsequently keep relays S^2 and S^3 energized, means operating if the engineer closes contact 71 upon a change from slow to stop conditions to energize all of said acknowledging relays and to keep them energized, a brake valve magnet, a main circuit for said magnet including back contacts of said relays S^2 and S^3 and a front contact of said relay R^3 , and other circuits for said magnet controlled by said R and S relays.

5. Train carried railway traffic controlling apparatus comprising three relays R^1 , R^2 and R^3 , controlled in such manner that relays R^1 and R^3 are energized under "authorized" conditions, relays R^1 and R^2 are energized under "approach restricting" conditions, relay R^1 alone is energized under "slow" conditions, and all three relays are de-energized under "stop" conditions; three stick relays S^1 , S^2 and S^3 , a manually operable acknowledging switch α having a normally open contact 71, means operating if the engineer closes contact 71 upon a change from authorized to approach restricting conditions to energize relays S^1 , S^2 and S^3 in succession and to subsequently keep relay S^3 energized, means operating if the engineer closes contact 71 upon a change from approach restricting to slow conditions to energize relays S^1 , S^2 and S^3 in succession and to subsequently keep relays S^2 and S^3 energized, means operating if the engineer closes contact 71 upon a change from slow to stop conditions to energize all of said acknowledging relays and to keep them energized, a brake valve magnet, means for energizing said magnet while relay R^3 is energized provided relays S^2 and S^3 are de-energized, means for energizing said magnet while relay R^2 is energized provided that relay S^3 is energized and relay S^2 is de-energized, means for energizing said magnet when relays R^3 and R^2 are de-energized and relay R^1 is energized provided relay S^2 is energized, and means for energizing said magnet when all three relays R^3 , R^2 and R^1 are de-energized provided that relays S^1 and S^2 are energized.

In testimony whereof I affix my signature.

RONALD A. McCANN.
